CLAIM

The ornamental design for a magnetic grip and device, as shown and described.

DESCRIPTION

FIG. 1 is a top perspective view of a first example embodiment of a magnetic grip and device in an expanded state showing an example usage;

FIG. 2 is a right side view thereof showing the example usage;

FIG. 3 is a upper perspective view thereof;

FIG. 4 is a lower perspective view thereof;

FIG. 5 is a right side view thereof;

FIG. 6 is a front view thereof;

FIG. 7 is a rear view thereof;

FIG. 8 is a left side view thereof;

FIG. 9 is a top view thereof; and

FIG. 10 is a bottom view thereof.

FIG. 11 is a right side view of the first example embodiment in a closed state showing the example usage;

FIG. 12 is a right side view thereof;

FIG. 13 is a front view thereof;

FIG. 14 is a rear view thereof;

FIG. 15 is a left side view thereof;

FIG. 16 is a top view thereof;

FIG. 17 is a bottom view thereof;

FIG. 18 is an upper perspective view thereof; and,

FIG. 19 is a lower perspective view thereof.
